CIRCUIT INTERRUPTER

James M. Cumming, Turtle Creek, Pa., assignor
to Westinghouse Electric Corporation, East
Pittsburgh, Pa., a corporation of Pennsylvania

Application May 25, 1943, Serial No. 488,357

17 Claims. (Cl. 200—150)

1

This invention relates to circuit interrupters in general and, more particularly, to circuit interrupters of the type which utilize the pressure created adjacent one arc to force fluid against another serially related arc to effect the latter's extinction.

An object of my invention is to provide an improved circuit interrupter in which an improved contact operating mechanism is provided to establish one or more serially related arcs very rapidly. It is desirable in the circuit breaker art to have very high speed operation, such as an interval of three cycles from the tripping of the breaker mechanism to the extinction of the arc formed, and to aid in this I provide contact operating means of very high speed.

Another object is to provide an improved contact operating means which will insure that the arcs are not only formed very rapidly, but also are formed in the desired sequence not only during the opening operation but also during the closing operation.

Another object is to provide an improved contact operating means having biasing means which not only biases the contact means toward the open circuit position, but also provides the desired contact pressure between the several contacts.

Another object is to provide an improved circuit interrupter in which at least one pressure generating arc and two interrupting arcs are established, and to dispose the arcs in the most effective position to effect their rapid extinction.

Another object is to provide an improved arc extinguishing unit in which the pressure generating arc is established at one end of the unit, a first interrupting arc is established intermediate the ends of the unit and a second interrupting arc is established at the other end of the unit. Preferably the second interrupting arc also provides a disconnect break when the second interrupting arc is extinguished.

Another object is to provide an improved contact operating means in which a contact arm is pivotally mounted at one end and to provide contact support means pivoted to an intermediate point of the contact arm.

Another object is to provide a pivoted contact arm with contact support means pivoted to an intermediate point of the contact arm, and to provide stop means carried by the contact support means. The arrangement operates during the circuit opening movement to first rotate the contact arm until the contact arm strikes the stop means, at which time both the contact arm

2

and the contact support means rotate together as a unit. Preferably disconnect means serially connected in the circuit mechanically operate the contact support means to effect the opening and closing of the interrupter.

Another object is to provide rotatable means for establishing a pressure generating arc and also rotatable means for establishing an interrupting arc, and to utilize the pressure created at the pressure generating arc to force fluid under pressure toward the interrupting arc to effect the latter's extinction.

Another object is to provide a rotatable means for establishing an arc which cooperates with 15 a second rotatable means which establishes a serially related arc, and also to provide linearly movable means for operating both the aforesaid means. Preferably the linearly movable means constitutes disconnect means in the open circuit 20 position of the interrupter.

Further objects and advantages will readily become apparent upon a reading of the following specification taken in conjunction with the drawings in which:

25 Fig. 1 is an elevational view, partly in section, of a circuit interrupter embodying my invention and shown in the closed circuit position;

Fig. 2 is an enlarged vertical sectional view of 30 one of the improved arc extinguishing units taken on the line II—II of Fig. 6, the parts being shown in the closed circuit position;

Fig. 3 is a view similar to Fig. 2, but showing the disposition of the several parts during the initial portion of the opening operation after the 35 pressure generating arc has been established;

Fig. 4 is a view similar to Fig. 2, but showing the disposition of the parts at a subsequent time during the opening operation when a pressure generating arc and two interrupting arcs have 40 been established;

Fig. 5 is a view in section taken on the line V—V of Fig. 4;

Fig. 6 is a view in section taken on the line 45 VI—VI of Fig. 4; and

Fig. 7 is a plan view in section taken on the line VII—VII of Fig. 4.

Referring to the drawings and, more particularly, to Fig. 1, the reference numeral 1 designates a tank filled to the level 2 with a suitable arc extinguishing fluid 3, in this instance oil. Depending from the cover 4 of the tank 1 are insulating bushings 5, 6 which enclose terminal conductor studs 7, 8. Secured to the lower ends 55 of the conductor studs 7, 8 are two identical arc

extinguishing units generally designated by the reference numeral 9.

An insulating operating rod 10 arranged for vertical reciprocating motion by suitable operating means, not shown, serves to move a conducting bridging member 11. The fully open circuit position of the conducting bridging member 11 is shown by the dotted lines in Fig. 1. Briefly, the circuit through the interrupter shown in Fig. 1 comprises the conductor stud 7, left-hand arc extinguishing unit 3, conducting bridging member 11, right-hand arc extinguishing unit 9 to terminal conductor stud 8.

Referring more particularly to Fig. 2, it will be observed that a clamp 13 is threadedly secured to the lower end of the conductor stud 7 and clamped thereto by the nut 14. Preferably integrally formed with the clamp 13 is a top metallic plate member 15, in which is threadedly secured a stationary pressure generating contact 16. Disposed intermediate the ends of the arc extinguishing unit 9 is a metallic contact plate 17. Interposed between the top metallic plate member 15 and the contact plate 17 is an insulating cylinder 18 which holds in position insulating rings 19, 20, the first of which have a larger inside diameter than the latter. The insulating rings 19, 20 form a substantially enclosed pressure generating chamber or a confined region generally designated by the reference numeral 21, and having a corrugated inner surface as formed by the rings 19, 20. An over-pressure relief valve 22 may be utilized to prevent excessive pressures being formed in the pressure generating chamber 21 which otherwise might possibly cause an explosion.

A plurality of, in this instance six, insulating tie rods 23 hold the several insulating plates in position comprising the unit 9. The tie rods 23 have enlarged head portions 24. The upper and lower tie rods 23, as shown in Fig. 5, have their lower ends threadedly secured to the metallic contact plate 17, whereas the other four insulating tie rods 23 extend through the entire unit 9 and have nuts 25 threadedly secured to their lower ends.

A contact arm 27 is pivotally mounted by means of the pivot pin 28 to the contact plate 17. The contact plate 17 has a bifurcated portion 29 (see Fig. 6) which accommodates the pivot pin 28. The contact arm 27 has a laminated resilient conducting portion 30 more clearly shown in Fig. 2. The laminated portion 30 preferably comprises a plurality of resilient metallic blades. Secured, as by soldering, to the left-hand end of the laminated conducting portion 30, as viewed in Fig. 2, is a movable pressure generating contact 31, which cooperates with the stationary pressure generating contact 16 to draw a pressure generating arc 32 as shown more clearly in Figs. 3 and 4.

A flexible conductor 33 has its left-hand end secured, as by spot welding, to the contact arm 27, and has its right-hand end, as viewed in Fig. 3, secured by the bolts 34 to the contact plate 17. A stationary interrupting contact 36 is rigidly secured, as by welding, to the contact plate 17, and cooperates with a first movable interrupting contact 37 to draw a first interrupting arc 38 more clearly shown in Fig. 4. The first movable interrupting contact 37 is disposed at one end of a conducting member 39, the other end of which constitutes a second movable interrupting contact 40. The second movable interrupting contact 40 cooperates with a third movable inter-

rupting contact 41 to draw a second interrupting arc 42 more clearly shown in Fig. 4.

The conducting member 39 is secured, as by the rivets 44, to two insulating plates 45 having a configuration more clearly shown in Figs. 2 and 6. The two insulating plates 45 and the conducting member 39 are rigidly secured together by the rivets 44 and move together as a unit. The two insulating plates 45 are pivotally mounted intermediate the ends of the contact arm 27 by means of the pivot pin 46. A spring guide rod 47 is also pivotally mounted on the pivot pin 46 and has a washer 48 slidable thereon. A compression spring 50 is disposed between the washer 48 and a second washer 49 disposed at the lower end of the spring guide rod 47, a nut 49 being threaded to the lower end of the spring guide rod 47 to obtain the desired tension in the compression spring 50.

The upper end of the spring guide rod 47 is bifurcated to form two legs 51, more clearly shown in Fig. 6. The legs 51 are disposed between the contact arm 27 and the two insulating plates 45 as more clearly shown in Fig. 6. An insulating stop pin 52 passes through the two insulating plates 45, the purpose for which will appear more clearly hereinafter. Disposed between the contact plate 17 and the bottom insulating plate 55 of the arc extinguishing unit 9 is a first interrupting arc chamber or first vented region, generally designated by the reference numeral 56, and a second interrupting arc chamber or second vented region, generally designated by the reference numeral 57.

The first interrupting arc chamber 56 comprises a plurality of suitably shaped insulating plates held in position by the insulating tie rods 23. The insulating plates are, in this instance, of two kinds. The first kind is designated by the reference numeral 58 and has an elongated slot 59 formed therein as more clearly shown in Fig. 6. The other kind of insulating plate is designated by the reference numeral 60 and is herein called a vent plate. The vent plate 60 has a vent slot 61 formed therein which in this instance has the same width as the slot 59 formed in the insulating plate 58. However, the vent slot 61 formed in the insulating vent plate 60 has a vent opening 62 more clearly shown in Fig. 6. Consequently, the first interrupting arc chamber 56 is vented to the region exterior of the arc extinguishing unit 9 by the vent openings 62.

Separating the first interrupting arc chamber 56 from the second interrupting arc chamber 57 is an insulating plate 65 having an opening 66 formed therein to accommodate the motion of the spring guide rod 47, and a passage 67 formed therein which serves to provide a fluid conducting passage between the first interrupting arc chamber 56 and the second interrupting arc chamber 57. The insulating plate 65 has a stop portion 68 which serves to limit the downward movement of the conducting member 39. An insulating tube 69 is positioned between the insulating plate 65 and the lowermost insulating plate 55. The tube 69 serves as a guide for the compression spring 50.

It will be observed that the washer 48 prevents fluid within the first interrupting arc chamber 56 passing through the opening 66, through the tube 69 and through the vent 70 provided in the bottom insulating plate 55. Consequently, no fluid passes through the opening 66, all of the flow from the first interrupting arc chamber 56 to the second interrupting arc chamber 57 taking place 75 through the passage 67. The bottom insulating

plate 55 has an opening 71 to accommodate the vertical reciprocating movement of the third movable interrupting contact 41.

The second interrupting arc chamber 57 comprises, in this instance, three kinds of insulating plates held in position by the insulating tie rods 23. The first kind is herein termed an insulating vent plate 74 and has a configuration more clearly shown in Fig. 7. The insulating vent plate 74 has a vent slot 75 formed therein which terminates into a vent opening 76 as more clearly shown in Fig. 7. The vent plate 74 has an aperture 77 formed therein to accommodate the insulating tube 69.

The second kind of insulating plate constituting the second interrupting arc chamber 57 is herein called an insulating splitter plate 78. It has a splitter portion 79 as a result of having a relatively short elongated slot 81 formed therein. The third kind of insulating plate has a slightly longer elongated slot 81 than the insulating splitter plate 78. The slots in the second interrupting chamber are of less width than in the first interrupting chamber to more effectively interrupt low current arcs.

The operation of the interrupter will now be explained. In the closed circuit position of the interrupter, as shown by the full lines in Fig. 1 and by Fig. 2, the electrical circuit passing through the interrupter comprises the terminal conductor 7, the clamp 13, top metallic plate member 15, stationary pressure generating contact 16, movable pressure generating contact 31, laminated portion 39, contact arm portion 27, flexible conductor 33, contact plate 17, stationary interrupting contact 36, first movable interrupting contact 37, conducting member 39, second movable interrupting contact 40, third movable interrupting contact 41, conducting bridging member 11 from whence the electrical circuit passes through the right-hand arc extinguishing unit 9 in a similar manner toward terminal conductor stud 8. When it is desired to break the electrical circuit passing through the interrupter, or in response to overload conditions in the circuit controlled by the interrupter, suitable operating mechanism, not shown, operates to move the insulating operating rod 10 downwardly. This downward movement of the insulating operating rod 10 also moves downwardly the third movable interrupting contact 41.

The downward movement of the third movable interrupting contact 41 causes the contact arm 27 to rotate in a counterclockwise direction about the pivot pin 28, and causes the insulating plates 45 and the conducting member 39 to rotate in a clockwise direction about the stationary interrupting contact 36 as a fulcrum.

This initial portion of the opening movement serves to draw the pressure generating arc 32 as shown more clearly in Fig. 3. The drawing of the pressure generating arc 32 within the pressure generating chamber 21 causes pressure to be formed therein. This pressure is vented through the first interrupting arc chamber 56 and through the vent openings 62, and also through the passage 67 and through the vent openings 76 provided in the second interrupting arc chamber 57.

The above described opening motion continues until the laminated portion 39 strikes the stop pin 52 as shown in Fig. 3. When this occurs, the contact arm 27, the two insulating plates 45 and the conducting member 39 rotate together as a unit in a counterclockwise direction about the

pivot pin 28. This motion, however, serves to draw the first interrupting arc 38. The second interrupting arc 42 is not drawn at this time since the third movable interrupting contact 41 remains in engagement with the second movable interrupting contact 40.

When the first interrupting arc 38 is drawn (see Fig. 4) there is the first opportunity for interruption of the electrical circuit through the interrupter, for the first interrupting arc 38 is subjected to a transverse cross-blast of fluid, in this instance oil, which is caused as a result of the pressure within the pressure generating chamber 21. Consequently, the pressure generating arc 32 forces oil against the first interrupting arc 38 and may cause the latter's extinction even before the second interrupting arc 42 is drawn. If such is the case, the electrical circuit through the interrupter will be interrupted, and the separation between the contacts 40, 41 will merely serve to provide the desired disconnect gap.

However, if the first interrupting arc 38 is not extinguished by the pressure generating arc 32 by the time that the conducting member 39 strikes the stop portion 68 of insulating plate 65, then the third movable interrupting contact 41 will separate from the second movable interrupting contact 40 to draw the second interrupting arc 42 as clearly shown in Fig. 4. Thus the pressure generating arc 32 serves to force oil not only against the first interrupting arc 38 but also through the passage 67 in the insulating plate 65 and across the second interrupting arc 42 and out through the vent openings 76 provided for the second interrupting arc chamber 57. The second interrupting arc 42 is forced by the oil flow through the passage 67 to the left, as viewed in Fig. 4, and against the splitter portions 79 of the insulating splitter plates 78. This greatly elongates the second interrupting arc 42 and facilitates its extinction. Also the lateral movement of the second interrupting arc 42 toward the left, as viewed in Fig. 4, brings it into contact with fresh oil of high dielectric strength disposed within the second interrupting arc chamber 57 and also disposed between the splitter portions 79 of the insulating splitter plates 78.

By a suitable restriction of the vent openings 62 in the first interrupting arc chamber 56, or even by the elimination of one of the vent openings 62 in the first interrupting arc chamber 56, the first interrupting arc chamber 56 may be somewhat enclosed to assist the pressure generating chamber 21 in forcing oil through the passage 67 and against the second interrupting arc 42 in the second interrupting arc chamber 57. In other words, if the first interrupting arc chamber 56 is partly enclosed it will act somewhat as a pressure generating chamber itself to cooperate with the pressure generating arc 32 in the pressure generating chamber 21 to facilitate the extinction of the second interrupting arc 42. In the arrangement shown in the drawings, however, the vent openings 62 are sufficiently large so that the pressure generating arc 32 forces oil transversely of the first interrupting arc 38 and out through the vent openings 62.

The vent openings 76 disposed in the second interrupting arc chamber 57 may be limited so that the second interrupting arc chamber 57 may act somewhat as an "explosion pot." Also if the second interrupting arc 42 has not been extinguished by the time that the third movable contact 41 has reached the opening 71 in the

bottom insulating plate 55, the second interrupting arc 42 will be subjected to a blast of oil as the second interrupting arc 42 is drawn through the opening 71 out of the unit 8. When one of the several arcs is extinguished, this will break the electric circuit through the interrupter and the third movable interrupting contact 41 and the conducting bridging member 11 will move downwardly to a position shown by the dotted lines in Fig. 1. This provides the desired disconnect gaps in clean oil to prevent reignition of the arcs as a result of voltage surges on the line.

The closing operation of the interrupter will now be explained. During the closing operation the third movable interrupting contact 41 moves upwardly to strike the second movable interrupting contact 40. Because of the stop pin 52 the conducting member 39, the two insulating plates 45 and the contact arm 27 will rotate together as a unit in a clockwise direction about the pivot pin 28 against the biasing action exerted by the compression spring 50. It will be observed that during this initial closing motion the compression spring 50 produces the desired contact pressure between the second and third movable interrupting contacts 40, 41. This motion continues until the first movable interrupting contact 37 strikes the stationary interrupting contact 36, at which time the conducting member 39 and the two insulating plates 45 rotate in a counterclockwise direction about the stationary interrupting contact 36 as a fulcrum, whereas the contact arm 27 rotates in a clockwise direction about the pivot pin 28 until the movable pressure generating contact 31 strikes the stationary pressure generating contact 16. This closes the electrical circuit through the interrupter.

It will be observed that after the first movable interrupting contact 37 has struck the stationary interrupting contact 36 that thereafter the clockwise rotative movement of the contact arm 27 is exceedingly rapid. Consequently, there is very little time for the arc which will form between the contacts 16, 31 during the closing operation to generate any gas and contaminate the oil within the pressure generating chamber 21. Also it will be noticed that during the initial portion of the opening operation, while the contacts 36, 37 are in engagement, that the elongation of the pressure generating arc 32 is exceedingly rapid and causes a great amount of pressure to be suddenly formed in the pressure generating chamber 21 because of the considerable speed of lengthening of the pressure generating arc 32.

It will be apparent that the contact pressure between the contacts 16, 31 is produced by the resiliency of the laminated portion 38 of contact arm 27. It will also be apparent that the compression spring 50 not only biases the entire contact mechanism toward the open circuit position but also produces the desired contact pressure not only between the contacts 40, 41 but also between the contacts 36, 37. This results because of the torque exerted by the compression spring 50 on the insulating plates 45 tending to cause a rotation of the insulating plates 45 in a clockwise direction about the contact 41 as a fulcrum.

It is apparent that the contact arm 27 rotates in a counterclockwise direction while the insulating plates 45 rotate in a clockwise direction during the opening operation until the contact arm 27 strikes the stop pin 32 thus permitting the contact arm 27 and the plates 45 to rotate together as a unit in a counterclockwise direction about the pivot pin 28 during the opening oper-

ation. Consequently, although the contact speed is greatly increased by the rotative movement of the parts, nevertheless, the desired sequence of arc drawing during opening and closing is always maintained.

Although I have shown and described a specific structure, it is to be clearly understood that the same was merely for the purpose of illustration and that changes and modifications may readily be made by those skilled in the art without departing from the spirit and scope of the appended claims.

I claim as my invention:

1. In a circuit interrupter, an arc extinguishing unit, a confined region within the unit, means for establishing a pressure generating arc within the confined region at one end of the unit, a first vented region, means for establishing a first interrupting arc intermediate the ends of the unit in the first vented region, a second vented region, means for establishing a second interrupting arc within the second vented region at the other end of the unit, and means utilizing the pressure created within the confined region at the pressure generating arc to force fluid under pressure into the first and second vented regions toward the two interrupting arcs to effect their extinction.

2. In a circuit interrupter, an arc extinguishing unit, a confined region within the unit, a first means for establishing a pressure generating arc within the confined region at one end of the unit, a first vented region, a second means to establish a first interrupting arc within the first vented region intermediate the ends of the unit, a second vented region, a third means for establishing a second interrupting arc within the second vented region at the other end of the unit, a portion of the third means also serving as disconnect means in the open circuit position of the interrupter by being withdrawable from the unit, and means utilizing the pressure created at the pressure generating arc within the confined region to force fluid under pressure into the first and second vented regions toward the two interrupting arcs to effect their extinction.

3. In a circuit interrupter, an arc extinguishing unit, a confined region within the unit, means for establishing a pressure generating arc within the confined region at one end of the unit, a first vented region, means for establishing a first interrupting arc within the first vented region intermediate the ends of the unit after the establishment of the pressure generating arc, a second vented region, means for establishing a second interrupting arc within the second vented region at the other end of the unit after the establishment of the first interrupting arc, and means utilizing the pressure created within the confined region at the pressure generating arc to force fluid under pressure into the first and second vented regions toward the two interrupting arcs to effect their extinction.

4. In a circuit interrupter, an arc extinguishing unit, a confined region within the unit, a first means for establishing a pressure generating arc within the confined region at one end of the unit, a first vented region, a second means to establish a first interrupting arc within the first vented region intermediate the ends of the unit after the establishment of the pressure generating arc, a second vented region, a third means for establishing a second interrupting arc within the second vented region at the other end of the unit after the establishment of the first interrupting arc, a portion of the third means also serving

as disconnect means in the open circuit position of the interrupter, by being withdrawable from the unit, and means utilizing the pressure created within the confined region at the pressure generating arc to force fluid under pressure into the first and second vented regions toward the two interrupting arcs to effect their extinction.

5. In a circuit interrupter, a first relatively stationary contact, a contact arm pivoted at one end and having a first movable contact supported thereon adjacent its other end, the first movable contact being cooperable with the first stationary contact to establish a first arc, a second relatively stationary contact, a second movable contact pivoted on and movable about an intermediate point of the contact arm, the second movable contact being cooperable with the second stationary contact to establish a second arc serially related with respect to the first arc.

6. In a circuit interrupter, a contact arm pivotally mounted on a stationary pivot, contact support means pivoted to an intermediate point of the contact arm, stop means carried by the contact support means, and means operating during the circuit opening operation to first rotate the contact arm until the contact arm strikes the stop means, and to thereafter rotate the contact arm and the contact support means together as a unit.

7. In a circuit interrupter, a substantially enclosed chamber, a vented chamber, a first contact means to establish a pressure generating arc within the enclosed chamber, the first contact means comprising a contact arm pivotally mounted on a stationary pivot, a second contact means to establish an interrupting arc within the vented chamber, the second contact means comprising a contact support member pivoted to an intermediate point of the contact arm, and means operating to first rotate the contact arm to establish the pressure generating arc and subsequently to rotate the contact arm and the contact support member together as a unit to subsequently establish the interrupting arc.

8. In a circuit interrupter, a first relatively stationary contact, a contact arm pivotally mounted on a stationary pivot and having a first movable contact adjacent its free end, the first movable contact being cooperable with the first stationary contact to establish an arc, a second relatively stationary contact serially related with respect to the first relatively stationary contact, contact support means pivoted to an intermediate point of the contact arm and carrying a second movable contact, the second movable contact being cooperable with the second stationary contact to establish an arc, stop means carried by the contact support means, and means for rotating the contact arm until the contact arm strikes the stop means to then permit the contact support means and the contact arm to rotate together as a unit.

9. In a circuit interrupter, a substantially enclosed chamber, a vented chamber, passage means extending between the chambers, a first relatively stationary contact, a contact arm pivoted at one end and having a first movable contact adjacent its free end, the first movable contact being cooperable with the first stationary contact to establish a pressure generating arc within the enclosed chamber, a second relatively stationary contact serially related with respect to the first relatively stationary contact, contact support means pivoted to an intermediate point of the contact arm and carrying a second mov-

able contact, the second movable contact being cooperable with the second stationary contact to establish an interrupting arc within the vented chamber, the two arcs being serially related, 5 stop means carried by the contact support means, means for rotating the contact arm until the contact arm strikes the stop means to then permit the contact support means and the contact arm to rotate together as a unit, and passage means interconnecting the two arcs.

10. In a circuit interrupter, a contact arm pivotally mounted at one end on a stationary pivot, contact support means pivoted to an intermediate point of the contact arm, stop means carried by the contact support means, and serially related disconnect means operating during the circuit opening operation to first rotate the contact arm until the contact arm strikes the stop means, at which time both the contact arm and the contact support means rotate together as a unit.

11. In a circuit interrupter, a first elongated rotatable means pivotally mounted at one end for establishing an arc, a second rotatable means 20 for establishing an arc pivotally mounted intermediate the ends of the first elongated rotatable means, and means for connecting the two arcs in series relation.

12. In a circuit interrupter, a first elongated rotatable means pivotally mounted at one end for establishing a first arc, a second means pivotally mounted intermediate the ends of the first elongated means for establishing a second arc, the two arcs being serially related, stop means carried by the second means, and means operating 35 during the opening operation so that the first and second means initially rotate in opposite directions until the first means strikes the stop means at which time both the first and second means rotate in the same direction.

13. In a circuit interrupter, a first elongated rotatable means pivotally mounted at one end for establishing a first arc, a second means pivotally mounted intermediate the ends of the first elongated means for establishing a second arc, stop means carried by the second means, and serially related disconnect means including a linearly movable contact striking the second means in abutting engagement operating during the opening operation so that the first and second means initially rotate in opposite directions until the first means strikes the stop means at which time both the first and second means rotate in the same direction, and the disconnect means being operable to draw a third arc between the linearly movable contact and the second means.

14. In a circuit interrupter, an arc extinguishing unit, a first pair of separable contacts one of which is pivotally mounted at one end within the unit, a second pair of separable contacts one of which is pivotally mounted intermediate the ends of one of the first pair of contacts, disconnect means for the unit comprising a third pair of separable contacts, means connecting the three pairs of contacts electrically in series, actuating means for the contacts operable to move one of the third pair of contacts, and the actuating means being operable to sequentially cause the separation of the three pairs of separable contacts.

15. In a circuit interrupter, an arc extinguishing unit, a confined region within the unit adjacent one end thereof, a first rotatable means for establishing a pressure-generating arc within 70 said confined region, a first vented region inter-

mediate the ends of the unit, a second rotatable means for establishing a first interrupting arc in the first vented region, a second vented region at the other end of the unit, means for establishing a second interrupting arc within the second vented region, and means utilizing the pressure created within said confined region at the pressure generating arc to force fluid under pressure into the first and second vented regions toward the two interrupting arcs to effect their extinction.

16. In a circuit interrupter, an arc extinguishing unit, a confined region within the unit adjacent one end thereof, a first rotatable means for establishing a pressure-generating arc within said confined region, a first vented region intermediate the ends of the unit, a second rotatable means for establishing a first interrupting arc in the first vented region, a second vented region at the other end of the unit, linearly movable means for operating both the first and second rotatable means and for establishing a second interrupting arc within the second vented region, and means utilizing the pressure created within the confined region at the pressure generating arc to force fluid under pressure into the first and second vented regions toward the two interrupting arcs to effect their extinction.

17. In a circuit interrupter, an arc extinguishing unit, a confined region within the unit adjacent one end thereof, a first rotatable means for establishing a pressure-generating arc within said confined region, a first vented region intermediate the ends of the unit, a second rotatable

means for establishing a first interrupting arc in the first vented region, a second vented region at the other end of the unit, linearly movable means for operating both the first and second rotatable means and for establishing a second interrupting arc within the second vented region, means utilizing the pressure created within the confined region at the pressure generating arc to force fluid under pressure into the first and second vented regions toward the two interrupting arcs to effect their extinction, and the linearly movable means being withdrawn from the unit to insert an isolating gap in the circuit in the fully open circuit position of the interrupter.
